BABY BOTTLE HOLDER

Richard L. Kausen and Judith L. Kausen, both of
20810 Avenue 204, Lindsay, Calif. 93247

Filed May 10, 1967; Ser. No. 7,153

Term of patent 14 years

(Cl. D83—8)

FIG. 1 is a perspective view of the baby bottle holder showing our new design in an operating position on a baby.

FIG. 2 is a somewhat enlarged top plan view thereof.

FIG. 3 is a bottom plan view thereof.

FIG. 4 is a side elevation thereof.

FIG. 5 is an elevational view of the opposite side from the side shown in FIG. 4.

FIG. 6 is a front elevation thereof.

FIG. 7 is a rear elevation thereof.

FIG. 8 is a perspective view thereof.

The broken line representation of the human form in FIG. 1 is shown for illustrative purposes only.

We claim:

The ornamental design for a baby bottle holder, as shown and described.
